UNITED STATES PATENT OFFICE.

LEWIS E. LEAROYD, OF DANVERS, MASSACHUSETTS.

LEATHER DRESSING OR FINISHING MACHINE.

SPECIFICATION forming part of Letters Patent No. 484,029, dated October 11, 1892.

Application filed July 16, 1891. Serial No. 399,732. (No model.)

To all whom it may concern:

Be it known that I, LEWIS E. LEAROYD, of Danvers, county of Essex, State of Massachusetts, have invented an Improvement in 5 Leather Dressing or Finishing Machines, of which the following description, in connection with the accompanying drawings, is a specification, like letters and figures on the drawings representing like parts.

10 This invention has for its object to improve the construction of leather dressing or finishing machines.

15 My invention comprehends a work-table, preferably made adjustable, and one or more dressing or finishing rollers adapted to be moved over the surface of the table, and means for positively rotating said dressing or finishing rollers as they are advanced over the table, and a liquid-containing tank or vessel 20 from which leads a suitable pipe arranged to supply the dressing or finishing rollers with any suitable liquid. The work-table is made to rock, so that first one and then the other end may be raised and lowered. A suitable 25 valve is provided for the pipe leading from the liquid-containing tank, which is automatically operated.

30 Figure 1 shows in side elevation a leather dressing or finishing machine embodying this invention; Fig. 2, a rear end view of the machine shown in Fig. 1; Fig. 3, a sectional detail of the carriage which supports the dressing or finishing rollers, taken on the dotted line $x-x$, showing one of the rollers in elevation; and Fig. 4, a sectional detail of the dressing or finishing rollers and supporting-carriage therefor.

35 The main framework comprises a base A and an inclined arm B. A shaft a , having its 40 bearings in the main framework, is driven by a belt-pulley a' thereon and carries a wheel a'' , provided with a wrist-pin b , which is connected with a slide-block c by a pitman b' . The slide-block c is mounted on a guide-rod 45 c' , secured to lugs $c'' c'''$ on the main framework. A roller-carrying frame h is attached to the slide-block c by screws 120 or otherwise. A belt-pulley b^2 is secured to the wrist-pin b , over which passes the belt b^3 , which in 50 turn passes over a pulley b^4 , mounted on a stud b^5 , which, as herein represented, is a continuation of the stud on the slide-block, to

which the pitman is connected. A sprocket-wheel b^6 is secured to said pulley b^4 , over which passes a sprocket-chain b^7 , which engages with 55 and drives two sprocket-wheels $b^8 b^9$, secured to shafts $b^{10} b^{12}$, having their bearings in the roller-carrying frame and carrying dressing or finishing rollers $b^{13} b^{14}$.

To the opposite end of the shaft b^{10} another 60 sprocket-wheel b^{10} is secured, which is connected by a sprocket-chain b^{30} with a sprocket-wheel b^{16} , (see dotted lines, Fig. 4,) secured to a shaft b^{17} , also having its bearings in the roller-carrying frame, said shaft b^{17} carrying 65 a dressing or finishing roller b^{18} . It will therefore be understood that the slide block c and roller-carrying frame serve as the carriage which supports the dressing or finishing rollers b^{13}, b^{14} , and b^{18} , and also I desire it 70 to be understood that one or more dressing or finishing rollers may be employed, as desired, although three are herein shown, and, further, that said roller-carrying frame may be detached and any other suitable form of 75 dressing or finishing tool provided.

By means of the crank motion herein shown the carriage supporting the dressing or finishing rollers will be reciprocated over the surface of the work-table d , and also by 80 means of the belt-pulley b^2 and its connections with said dressing or finishing rollers, the latter will be rotated very rapidly independently of the movement given to them by the carriage, to thereby work into the leather 85 laid on the work-table the dressing, coloring-matter, or other material desired, said rollers acting as calender-rollers.

A liquid-containing tank or vessel C is supported in any suitable manner, from which 90 leads a flexible pipe e , connected to a valve-case e' , provided with a delivery-nozzle e^2 , which is adapted to deliver the liquid material to the dressing or finishing rollers.

The valve-case e' is borne by the carriage 95 c , and the valve in said valve-case has an arm e^3 projecting from it, which as the carriage is moved upward in the direction of the arrow, Fig. 1, strikes a pin 2 on the main framework at or near the limit of upward 100 movement of the carriage to turn the arm e^3 and close the valve, and at or near the limit of movement of the carriage in the opposite direction a pin 3 is provided, which is formed

integral with or secured to an arm 4 of a bell-crank lever pivoted to the main framework at 5, the opposite arm 6 of said bell-crank lever being connected by a connecting-rod 7 with a hand-lever 8, pivoted to the main framework at 9. When the arm e^3 strikes the pin 3, the valve is opened and the liquid material will be delivered to the rollers as the carriage is moved in the direction of the arrow. By moving the hand-lever 8 and throwing the pin 3 out of the path of movement of the arm e^3 the valve will not be opened as the carriage is reciprocated.

The work-table d is inclined, as shown in Fig. 1, or it may be horizontal, and is adjustably arranged on an inclined or horizontal bed d' , as the case may be, which bed is supported on independent toggle arms or levers d^2 d^3 at the front and rear ends, said arms or levers being connected to the top side of the base d^4 , adapted to be moved vertically in guide-frames d^5 d^6 and resting on cam-levers d^8 d^9 . These levers d^8 d^9 are pivoted to the guide-frames, as shown, and are connected to a foot-lever d^{10} , pivoted at d^{12} to one of the said guide-frames.

By depressing the foot-lever the base-plate d^4 may be raised to raise the inclined table d vertically.

The toggle-levers d^2 are connected by a series of levers with a lever f , pivoted at f' , and the toggle-levers d^3 are connected by a series of levers f^2 , pivoted at f' , said levers f f^2 extending vertically and lying in the path of movement of pins, as 12 13, on the wheel a^2 .

Springs f^3 f^4 are connected to the levers f f^2 and act to normally keep the toggles d^2 and d^3 in perpendicular position or alignment.

As the wheel a^2 revolves in the direction of the arrow thereon the lever f will be moved and the toggle d^2 shortened to drop the front end of the table a short distance, and thereafter the pin 13 will strike the pivoted lever f^2 and shorten the toggle d^3 and drop the rear end of the work-table a short distance. Hence said table will be made to rock. At such time the table will leave the leather dressing or finishing tool, so that the skin may be moved along.

I do not desire to limit my invention to the particular means herein shown for reciprocating the carriage c , although the construction shown I deem preferable; nor do I desire to limit myself to the particular means herein shown for revolving the dressing or finishing rollers, as it is obvious that they may be revolved by other means; nor do I desire to limit myself to the particular means herein shown for rocking the work-table.

I claim—

1. In a leather dressing or finishing machine, a work-table, supports at its ends, and means, substantially as described, for positively moving said supports independently and alternately to thereby raise and lower the ends of the table at different times, combined with one or more dressing or finishing tools

and means for moving them over the table, substantially as described.

2. In a leather dressing or finishing machine, a work-table, independent movable supports at its ends, and means to positively move said supports independently and at different times to thereby cause the table to rock, combined with one or more rotatable dressing or finishing tools, means for moving them, and a straight guide, substantially as described.

3. In a leather dressing or finishing machine, a work-table, combined with toggles at each end to support it and independent means for positively moving each set of toggles separately and alternately to rock the table, substantially as described.

4. In a leather dressing or finishing machine, a work-table, a bed to support it, and means to adjust the table with relation to the bed, combined with toggles at each end of the bed to support it and independent means for positively moving each set of toggles separately and alternately to rock the bed and its table, substantially as described.

5. In a leather dressing or finishing machine, a work-table, independent toggles at each end supporting it, and a rising and falling base supporting said toggles, combined with pivoted levers, as f^2 , respectively connected to said toggles, and controlling-springs f^3 f^4 to normally retain said toggles extended, and devices to turn first one and then the other of said levers on their pivots, substantially as described.

6. In a leather dressing or finishing machine, a work-table, toggles at each end supporting it, and a rising and falling base supporting said toggles, combined with pivoted levers, as f^2 , respectively connected to said toggles, and controlling-springs, and a wheel, as a^2 , having pins 12 13, located substantially diametrically opposite each other, for moving said levers f^2 to impart a rocking motion to said table, substantially as described.

7. In a leather dressing or finishing machine, a work-table, one or more dressing or finishing tools, and means for moving the same over the table, combined with a liquid-containing tank, a delivery-pipe, and an automatically-operated valve moving with said tools and actuated by devices independent thereof, substantially as described.

8. In a leather dressing or finishing machine, a work-table and one or more dressing or finishing tools reciprocated by a carriage, combined with a liquid-containing tank, a delivery-pipe leading to the tools, a valve, and operating devices therefor at each end of the movement of the carriage to open said valve at one end and to close it at the other end, substantially as described.

9. In a leather dressing or finishing machine, a work-table and one or more dressing or finishing tools reciprocated by a carriage, combined with a liquid-containing tank, a delivery-pipe leading to the tools, a valve, and operating devices therefor at each end of the

movement of the carriage to open said valve at one end and to close it at the other end, and a hand-operated lever connected with one of said operating devices by which its co-operating with the valve is prevented, substantially as described.

5 In testimony whereof I have signed my

name to this specification in the presence of two subscribing witnesses.
